UNITED STATES PATENT OFFICE.

ARLINGTON MOORE, OF NEW YORK, N. Y., ASSIGNOR TO MOORE INVENTIONS CORPORATION, OF WORCESTER, MASSACHUSETTS, A CORPORATION OF MASSACHUSETTS.

INTERNAL-COMBUSTION-ENGINE DECARBONIZER.

Application filed September 27, 1922. Serial No. 590,859.

My invention relates to a decarbonizer for internal combustion engines.

The primary object of the invention is to provide an efficient, inexpensive and conveniently operated means for preventing the accumulation of carbon deposits within the engine cylinders, and for loosening and removing carbon deposits which have been formed therein.

10 Another object of the invention is to increase the combustibility of the gases drawn into the engine cylinders on the induction stroke by causing small quantities of steam to be mixed therewith before being drawn into the engine cylinders, thereby rendering the operation of the engine more efficient and economical.

Other objects will appear from the following description of the invention.

20 In the accompanying drawing, I have illustrated an embodiment of my invention, but same is for illustration only and for affording an understanding of the invention and not for limitation thereof. Fig. 1 is a 25 side view with parts broken away showing a decarbonizer embodying my invention installed on the internal combustion engine of an automobile. Fig. 2 is a sectional view of a vaporizer screwed into the exhaust manifold of the engine. Fig. 3 is a top view of the vaporizing device. Fig. 4 is a sectional view of the decarbonizer control knob, and Fig. 5 is a fragmentary view showing water jet openings, looking in the direction of the 30 arrows on line 5—5, Fig. 2.

The water vaporizing apparatus is formed as a metal casing 10 containing a preferably cylindrical steam chamber 12, and provided on the bottom 14 with a screw threaded projecting portion 16, adapted to be screwed into the exhaust pipe or manifold 18 of the engine 20. A heat conductor 22, such as a round copper bar or the like, is inserted through hole 24 in the bottom wall 14 of the 45 steam chamber, with the top portion 26 extending into the steam chamber 12, and the opposite end portion 28 thereof extending into the exhaust manifold 18. The conductor 22 is held in place as by means of 50 pin 30 passing through the portion 16 of the casing.

A drain opening 32 is provided in the steam chamber 12, near the bottom, and is

adapted to be opened and closed, as by means of a petcock 34.

Another opening 36 is provided in the opposite side wall 38, about midway of the steam chamber 12, for the reception of water inlet pipe 40, which may lead from any place in the engine water circulating system, preferably from the top of the engine near the water filling opening, or in the case of an air cooled engine, a separate source of water supply may be provided. In Fig. 1 water inlet pipe 40 is shown connected to the water jacket manifold 42. The water preferably enters the steam chamber through a spray nozzle. In the form shown, a plug 44, having several pinholes 46 therein is placed in the mouth of water inlet pipe 40 which enters the opening 36 in the steam chamber 12, thereby constricting the water inlet opening and causing the water drawn in therethrough to enter the steam chamber 12 and come into contact with the heating element 22 in the form of a mist or fine spray.

To prevent dirt and sediment from entering the steam chamber 12, a strainer 48 of conventional design is interposed in the water inlet pipe 40. This strainer comprises a T-shaped casing 50, a fine circular screen 52 and a plug 54. The water enters the strainer through the water pipe 40', passes through the screen 52, and out through the water pipe 40 into steam chamber 12. The sediment collected drops to the bottom of screen 52 and is removed from time to time by unscrewing plug 54.

An auxiliary outlet chamber 56 is provided within the casing 10, being separated therefrom by the partition wall 58, and valve seat 60 is provided in said partition. A valve 62, preferably of the poppet type, is provided to control the communication between chambers 56 and 12. The valve is mounted so that the head 64 thereof is adapted to be seated in valve seat 60, and in the form shown, poppet valve 62 is provided with front and rear stems, the rear stem 66 being received and guided in the guide opening 68 to secure accurate seating of the valve. The valve stem 70 on the other end of valve 62 extends through the packed gland 72 provided in the casing 12. Valve 62 is normally held closed by spring 74, and the valve is adapted to be opened against said spring

by suitable means applied to the projecting end of valve stem 70. In the form shown, wire 76 is secured to the projecting end of the valve stem and leads to a control knob 78, which may be mounted at any desirable location, but is preferably mounted on the dashboard, as indicated in Fig. 1. The extent of opening of the valve may be controlled in any desired way, as by the provision of stop nuts 80, 82, screwed on the stem 84 of knob 78. The control means are preferably so arranged that the valve 62 can be left open if desired. One means of effecting such result consists in the provision of the bearing 86 for knob stem 84 with a raised or projecting portion 88, and the provision of a corresponding recess 90 upon the neck 92 of knob 78. When the knob 78 is pulled outwardly to the full extent permitted by stop nuts 80, 82, and given a partial turn, the valve will be held open by the bearing projection 88, and may be released by the knob 78 being turned to the position shown in Fig. 4, bringing the recess 90 into register with the bearing projection 88.

Steam outlet pipe 94 leads from the opening 95 in the upper portion of the chamber 56, to the intake manifold 98 of the engine.

The operation of the device is very simple. When it is desired to rid the engine cylinders of an accumulation of carbon, the operator of the vehicle simply pulls out knob 78 on the dashboard when the engine is running, and keeps it out for a short space of time, say half a minute, and then releases the knob. Outward movement of knob 78 opens valve 62, and on the induction strokes of the engine, water from the circulation system is drawn into the steam chamber 12 in a spray or very fine mist. As soon as this mist strikes the hot surface of heat conductor 22 it flashes into steam and is drawn into the intake manifold through steam outlet pipe 94, and consequently enters the engine cylinders. The introduction of steam into the engine cylinders tends to prevent carbon formation therein and to cause the carbon which has accumulated to be dislodged and blown out through the exhaust pipe with the exhaust gases. It will be noted that water is supplied to the vaporizer only when valve 62 is opened, and the water is drawn into the vaporizer chamber by the suction from the intake manifold. If any water should be converted into steam when the valve 62 is shut, no harm is done as the steam merely backs up into the water supply pipe.

If the engine is very badly carbonized, a quarter twist of the control knob 78, as above explained, serves to keep valve 62 only slightly open and comparatively small quantities of steam enter the engine cylinders. If this is allowed to continue for some time while the engine is running, the engine cyl-

inders will be substantially freed from carbon and greater engine efficiency will result.

Engine knocking due to carbon deposits can be easily detected when travelling up-hill, and when such knocking is heard, the operator can make use of the decarbonizer in the above described manner. If it is desired to introduce kerosene or other fluid into the engine, as is sometimes done, same may be introduced into the chamber 12 through the petcock 96, preferably when the engine is cool or comparatively cool, and will be drawn into the engine upon operating same with the valve 62 opened.

It is apparent that numerous other advantages can be secured with the device of the present invention, in addition to the one above described, such as greater combustibility of the intake charges due to a more moist mixture, etc.

The device is simply constructed and operates automatically, requiring very little attention on the part of the operator. No extra supply of water is required inasmuch as the water circulation system supplies the small quantity of water necessary. While it is possible to make continuous use of the decarbonizer, if desired, this is not necessary as satisfactory results can be secured by occasional use for short periods. Thus the attention usually required to keep a constantly operating device in good working condition is not necessary with my invention, and it is always ready for use when needed by merely pulling a control knob on the dashboard to open the valve communicating with the intake manifold.

Changes and modifications may be resorted to within the scope of the claims without departing from or sacrificing the advantages of my invention.

I claim:

1. A decarbonizer for an internal combustion engine comprising a hollow steam chamber supported on the exhaust manifold of the engine, a heat conductor projecting into said steam chamber and also into said exhaust manifold, means for supplying water from the circulation system to the steam chamber, means for conducting the steam to the intake manifold, and a valve in said steam chamber for controlling the generation of steam and the supplying thereof to the intake manifold.

2. A decarbonizer for an internal combustion engine comprising a hollow steam chamber supported on the exhaust manifold of the engine, a heat conductor extending into the interiors of the steam chamber and the exhaust manifold respectively, means for supplying water in a mist or fine spray to the steam chamber, means for conducting the steam to the intake manifold, a spring opposed poppet valve for controlling the de-

livery of steam to the intake manifold, and means connected to the poppet valve to control the functioning thereof.

3. A decarbonizer for an internal combustion engine, comprising a hollow steam chamber adapted to be supported on the exhaust manifold of the internal combustion engine, a heat conductor extending from the steam chamber into the exhaust manifold, a water inlet pipe leading into the steam chamber and so positioned as to deliver the water against the heat conductor, a strainer interposed in the water inlet pipe, a spring opposed poppet valve disposed within the steam chamber, and a steam delivery pipe leading to the intake manifold of the internal combustion engine.

4. A decarbonizer for an internal combustion engine, comprising a hollow cylindrical steam chamber adapted to be supported on the exhaust manifold of the engine, a heat conductor projecting from the steam chamber into the exhaust manifold, a water inlet pipe leading into the steam chamber, a plug 20 with a plurality of pinholes therein positioned in the mouth of the water inlet pipe, said water inlet pipe being so arranged that a mist or fine spray from said plug is directed against the heat conductor, a spring 25 opposed poppet valve horizontally disposed in the top portion of the steam chamber and seated on a valve seat formed within the top 30

portion of the steam chamber and integral therewith, and a steam delivery pipe leading from the portion of the steam chamber beyond the valve to the intake manifold of the engine.

5. A decarbonizer for an internal combustion engine comprising a hollow steam chamber supported on the exhaust manifold of the engine, a heat conductor projecting from said steam chamber into said exhaust manifold, means for supplying water from the circulation system to the steam chamber, means for conducting the generated steam to the intake manifold of the engine, a spring opposed poppet valve in said steam chamber controlling the generation of steam and delivery thereof to the intake manifold, and control means for controlling the operation of the poppet valve from a distance.

6. In a decarbonizer for internal combustion engines, a hollow casing, means for admitting water to the casing, and a massive heat conductor of good heat conducting material, such as copper, having one end projecting into the chamber in the hollow casing and occupying a major portion of the space in said chamber, and the other end projecting directly into the path of hot exhaust gases.

In testimony whereof, I have signed my name hereto.

ARLINGTON MOORE.
